UNITED STATES PATENT OFFICE.

SOL EINSTEIN, OF CINCINNATI, OHIO, ASSIGNOR, BY MESNE ASSIGNMENTS, TO CINCINNATI GRINDERS INCORPORATED, OF CINCINNATI, OHIO, A CORPORATION OF OHIO.

METHOD OF GRINDING.

Application filed August 17, 1925. Serial No. 50,738.

This invention relates to abrading and devised and may be designated as an "in-feed grinder". In the in-feed grinder the entire length of the surface to be ground is in contact with the abrading surface of the grinding wheel throughout the grinding 55 operation, and the piece is not fed between the wheels axially, but is inserted between the wheels. This is commonly done while the latter are slightly withdrawn from each other, but such separation is not always necessary. After insertion of the work 60 piece, the wheels if they have been separated are fed in, i. e., moved automatically or manually toward each other until they are spaced apart a definite distance. At the end of such feeding in the piece is allowed to

run a short time for finish. When the grinding has been completed the work piece 65 is ejected. This may be done without separation of the wheels, or after the wheels have been slightly separated to release it. 70 In such grinding the grinding wheel may be oscillated slightly in an axial direction to distribute the wear on the wheel and assure the retention of its true surface. 75

As stated, the in-feed machine was devised 80 primarily for the purpose of acting on those forms of work blank which are not susceptible of being fed axially between the wheels, but I have discovered by experimentation and tests that the operative characteristics of the two types of machine are 85 inherently different, and that, for certain classes of work, they are complementary to each other and may be conjointly used for the commercial production of finished pieces 90 which cannot be so well produced, or which cannot be so economically produced, by either machine alone.

The in-feed grinder can be used to remove 95 a larger amount of metal than can the through-feed grinder. If the wheels are fed, the cut may be made progressively in a radial direction and a relatively deep cut can be effected gradually. Operating on a work blank which is out of round or slightly tapered the in-feed grinder, when properly adjusted, has an inherent tendency to reduce that work blank to true cylindrical 100 form. The through-feed grinder can make only a limited cut and makes this progressively from end to end. Hence its ability to true up blanks that come to it tapered or out of round is limited. 105

The through-feed grinder is not generally adapted, however, for shouldered pieces and tapered pieces, and to grind such pieces another type of centerless grinder has been

While in-feed grinding is capable of producing finished pieces of the utmost accuracy, it is obvious that if this grinder be used to remove a considerable amount of metal, its precision will necessarily be impaired during the production of a relatively small number of pieces. If the machine be required merely to perform a rough-grinding operation, the product can be held quite easily within the limits necessary for rough-grinding, and the rough-ground product will be true in form and susceptible of successful finish-grinding in a through-feed grinder.

My process, therefore, in the best form known to me contemplates rough-grinding the blank by the in-feed method, that is, by placing it between the wheels in position to contact with the grinding wheel throughout its entire length and then moving the wheels one toward the other until there is a definite interval between the wheels, the grinding being effected as the wheels approach each other. At the termination of this operation, the wheels are separated and the rough-ground piece is ejected. This rough-grinding operation not only brings the piece approximately to size, but brings it to a truly round and truly cylindrical form. The resulting rough-ground piece is then in an ideal condition for finishing by the through-feed method, and since the through-feed method is much faster, requires far less supervision, and can be carried out with a much less expensive machine, the final step of finish-grinding by the through-feed process offers many commercial advantages.

Furthermore, a through-feed grinding operation starting with a truly cylindrical blank is an operation of the utmost precision because the blank moves across the face of both wheels and the finished diameter throughout its length results from successive contacts with the entire face of the grinding wheel. Consequently there can be no localized defects occasioned by slight irregularities in the face of the grinding wheel.

In the accompanying drawing I illustrate by diagram my improved process. 1 represents the grinding wheel and 2 the regulating wheel of an in-feed grinder whose work rest is shown at 3. The work piece or blank is shown at 4. The directions of rotation of the grinding wheel and regulating wheel are indicated by arrows, while the opposed arrows 5 indicate diagrammatically that the regulating wheel is fed toward and from the grinding wheel.

The above grinding elements are illustrated in side elevation. The grinding elements of the through-feed grinder are illustrated in edge elevation in order to bring out the relation of the work rest and the skewing of the regulating wheel. The grinding wheel is illustrated at 6, the regulating

wheel at 7, and the work rest at 8. Work pieces 4, after ejection from between the wheels 1 and 2, are fed to the wheels 6 and 7 by means of an inclined trough 9 which discharges them upon the work rest 8 in position to be gripped by the wheels 6 and 7 and fed axially between the wheels. During movement between the wheels the work piece is rotated, the wheel 7 regulating the rotation and the feed and the wheel 6 performing an abrading action, so that the finished work pieces discharge from the machine down a chute or trough 10.

While a single finish-grinding operation is ordinarily sufficient, I illustrate in the drawing the possibility of using more than one such finish-grinding operation. The second finish-grinding is conducted in a through-feed grinder consisting of a grinding wheel 11, regulating wheel 12, and work rest 13. The work pieces from the discharge trough 10 of the first through-feed grinder are supplied to the feed trough 14 of the second through-feed grinder which directs them to the work rest 13. From the work rest 13 they are discharged by means of a chute 15. In cases where the utmost precision is desired a series of finish-grinding operations may be used, the machines being so adjusted that each successive machine removes less stock than its predecessor. In this way the grinding wheel of the last finish-grinding machine is subjected to the minimum wear and its precision is thus maintained unimpaired for a longer period of operation.

While I suggest the use of separate machines, it should be appreciated that a single centerless grinder can be set up to operate either on the in-feed principle or on the through-feed principle. This being the case, it is obviously practicable to set the same machine up for the rough-grinding operations on the in-feed principle and then, after a sufficient quantity of rough-ground blanks has been produced, to set up the same machine to operate on the through-feed principle and use it to finish-grind these same blanks. Hence I do not imply any necessary limitation to the use of distinct machines, the invention residing in the steps of the process and the order in which these steps are performed rather than in the particular machine or machines used to perform them.

The process takes advantage of the best features of both types of grinding. Starting with an over-sized blank of inaccurate form, it reduces this blank to accurate form with very slight over-size. The rough-ground blank thus produced is then peculiarly susceptible to successful finish by the through-feed grinding process, and the final product is of the utmost precision. In this way it is possible to produce on a commer-

cial scale a finished product which surpasses in quality that heretofore produced by centerless grinding methods, notwithstanding the fact that those methods far exceeded the 5 precision of any known method of grinding on centers. In fact, conventional centerless grinding methods have enabled manufacturers in the motor car industry to increase their production rate, reduce their production 10 costs, and at the same time produce a finished product with plus and minus tolerances one-fourth those customarily set for the highest grade of work by the center grinding method. The present method is 15 a further advance in the same direction.

What I claim is:

1. That method of producing a finished cylindrical work piece by centerless grinding which consists in rough-grinding a blank 20 by the centerless in-feed method and thereafter finish-grinding said blank by the through-feed centerless grinding method.

2. That method of producing a finished cylindrical work piece by centerless grinding which consists in rough-grinding a blank 25 by supporting it on a work rest between a regulating wheel and a grinding wheel running at appropriate speeds, and then feeding said wheels one toward the other until a 30 definite interval is presented between said wheels, and finally feeding said blank axially upon a work rest between and beyond op-

posed regulating and grinding wheels spaced appropriate fixed distances apart to effect the desired finishing cut, said wheels being 35 driven at appropriate differential speeds.

3. That method of producing finished cylindrical work pieces by centerless grinding which consists in rough-grinding a blank 40 by the in-feed centerless method and thereby rendering it truly cylindrical and reducing its size by a substantial amount to a diameter slightly in excess of the desired finished diameter, and then finish-grinding said blank by one or more finish-grinding 45 operations conducted by the centerless through-feed method.

4. That method of producing finished cylindrical work pieces by centerless grinding which consists in rough-grinding a blank 50 by the in-feed centerless method whereby the diameter of the blank is reduced a substantial amount to a diameter slightly in excess of the finished diameter, and then subjecting said blank to a series of finish-grinding operations, each conducted on the centerless through-feed method, and each successive finish-grinding operation reducing the diameter by a less amount than the preceding grinding operation.

In testimony whereof I have signed my name to this specification.

SOL EINSTEIN.
